PIPE WRENCH

William O. Thewes, North Ridgeville, Ohio, assignor to The Ridge Tool Company, North Ridgeville, Ohio, a corporation of Ohio

Application October 26, 1934, Serial No. 750,179

4 Claims. (Cl. 81—105)

This invention relates to pipe wrenches, and the primary object of the same is to provide a wrench of this type which may be manufactured and assembled at a relatively low cost and which 5 at the same time embodies improved features as regards strength, working action and neatness in appearance and design.

The foregoing and other objects and advantages will become apparent in view of the following description taken in conjunction with the drawing, wherein:

Figure 1 is a view in side elevation of a wrench embodying the features of the invention;

Fig. 2 is a section taken on the line 2—2, Fig. 1; Figs. 3 and 4 are sectional views substantially similar to Fig. 2 but showing different types of jaw-housing springs and anchoring members therefor; and Figs. 3a and 4a are detail views of parts used in the forms shown in Figs. 3 and 4.

Referring to the drawing in detail, the reference numeral 5 designates the handle portion of the wrench and 6 the fixed jaw portion having fixed thereon a jaw plate 7. The movable jaw is indicated at 8 and is formed with the usual threaded shank 9 adapted for longitudinal movement in a longitudinal opening 10a formed in a yoke member or housing 10 and is provided with an adjusting nut 11. The housing is provided with a front portion through which the fixed jaw portion 6 extends and a rear portion which houses the shank of the movable jaw.

The present invention is centered around the construction and cooperative arrangement of the housing 10, springs 12 and fixed jaw portion 6. The housing 10 is pivoted at 10b to the fixed jaw portion 6 and is provided with a transverse opening or recess 13 in which the adjusting nut 11 is mounted. The springs 12 are of the coil or compression type, and in the form of the wrench shown in Figs. 1 and 2, said springs are substantially cone-shaped with the reduced end of each seated in through-bores or recesses 14 and 14a formed in opposed walls of the longitudinal opening 15 of the housing 10, and the free ends thereof bearing against opposed sides or edges of the fixed jaw portion 6 and resiliently maintaining the housing 10 and through the latter the movable jaw 8 in a neutral or floating position with respect to the fixed jaw 7.

There are certain important advantages provided by the foregoing construction, among which may be mentioned the following:

The handle 5 and its integral fixed jaw portion 6 may be formed free of holes or recesses such as are generally necessary in certain other types

of pipe wrenches to accommodate the attachment of leaf springs or other parts, which holes or recesses have a tendency to weaken a wrench at the point where the greatest stress is applied in service. The springs 12 exert their neutralizing or jaw-floating pressure at diametrically opposed points on the housing 10 and do not have the tendency to become unequalized or displaced oftentimes present in wrenches embodying springs of the leaf type or other types of differently located 10 springs, and this combined with the fact that the springs 12 may be relatively strong while at the same time the movable jaw may have a fairly snug fit and yet be free for unhindered adjustment in the opening 10a formed in the rear portion 5 of the housing 10 results in a highly improved working action with more pep throughout the life of the wrench. The springs 12 may be easily replaced at a negligible cost, and the wrench as a whole may be manufactured and 20 assembled at a relatively low cost without sacrificing quality. There are no protruding parts to scratch the hands or otherwise annoy the user of the wrench, and the latter has a generally neat appearance.

In Figs. 3 and 3a, the arrangement is such as to produce the same advantageous results found in the wrench shown in Fig. 1, but in this instance the springs 12a are carried by a holder 16 which, as shown, is formed of a strip of resilient 30 sheet metal which is snapped in place in the opening 15 of the housing 10c. If desired, the walls of said opening may be formed with a shallow recess in which the holder 16 may be seated to insure against displacement thereof. 35 The holder 16 is preferably formed with ears 16a in which the one end of each of the springs 12a is inserted, said ears preferably being formed simply by punching the metal of the holder 16 inwardly. With this construction it is not necessary to form holes 14 and 14a in the housing as in Figs. 1 and 2.

In Figs. 4 and 4a a further modified type of spring construction is shown. In this instance the spring 12b may be made in one piece, as 45 shown in detail in Fig. 4a, preferably consisting of a single piece spring wire which is bent into the form of coil springs at opposite extremities thereof and having side portions which normally bear against the side walls of the housing. In 50 this instance also it may be desired to form a shallow recess in which to seat the spring or the side portions thereof. In Figs. 3 and 4, the fixed jaw portion is indicated at 6a and the shank of the movable jaw at 9a.

It will be noted that in each of the forms shown, the neutralizing springs are located in substantially the same positions and are of substantially the same type and in conjunction with the construction and mounting of the housing 10 effect the same advantageous results.

It will be understood that certain minor changes in structure and design may be adopted within the scope of the invention as defined by the 10 appended claims.

I claim:

1. A pipe wrench comprising a handle and a fixed jaw portion formed integrally therewith and having a fixed jaw thereon, a movable jaw having 15 a shank, a jaw housing pivotally connected to the fixed jaw portion and having a front portion through which the fixed jaw portion extends and a rear portion through which the shank of the movable jaw extends, a pair of opposed coil springs mounted in the front portion of said housing, and means for retaining said springs in 20 position in said housing, said means comprising a sheet metal holder which is mounted in the front portion of said housing and is provided 25 with ears in which the one end of each of said springs is inserted.

2. A pipe wrench comprising a handle and a fixed jaw portion formed integrally therewith and having a fixed jaw thereon, a movable jaw 30 having a shank, a housing for the movable jaw pivotally connected to the fixed jaw portion, and coil springs disposed in opposed relation in the front portion of said housing and bearing against opposed sides of the fixed jaw portion to thereby 35 maintain the housing and the movable jaw car-

ried thereby in a floated position with respect to the fixed jaw, said springs being formed of a single piece of wire which has its opposite extremities bent into the form of coil springs and its central portion connecting said springs and bearing against the side walls of the housing to thereby retain the spring in position in said housing.

3. In a pipe wrench, a floating jaw, a housing therefor, a support for the housing, said housing being pivoted at one extremity to said support and at its opposite extremity having a portion which encompasses said support, coacting coil springs disposed on opposite sides of said support and bearing against said portion of the housing to thereby maintain the housing and the jaw carried thereby in a floating position, and means for holding said springs in frictional engagement with said portion to thereby avoid the formation of weakening spring-seating recesses in either 20 the housing or support.

4. A pipe wrench comprising a handle and a fixed jaw portion thereon, a movable jaw having a shank, a jaw housing pivotally connected to the fixed jaw portion and having a front portion 25 through which the fixed jaw portion extends and a rear portion through which the shank of the movable jaw extends, a pair of opposed coil springs mounted in the front portion of said housing, and means for retaining said spring in 30 position in said housing comprising a sheet metal holder which is mounted in the front portion of said housing and having means for holding the springs in position.

WILLIAM O. THEWES. 35
